United States Patent Office.

CHARLES W. WEST, OF SHILOH, ASSIGNOR TO HIMSELF AND OSCAR A. DOUGLAS, OF BRIDGETON, NEW JERSEY.

Letters Patent No. 97,999, dated December 14, 1869.

IMPROVEMENT IN PAPER-FILES.

The Schedule referred to in these Letters Patent and making part of the same.

To all whom it may concern:

Be it known that I, CHARLES W. WEST, of Shiloh, Cumberland county, New Jersey, have invented a new and improved Paper-File; and I do hereby declare that the following is a full, clear, and exact description thereof, which will enable others skilled in the art to make and use the same, reference being had to the accompanying drawings, forming part of this specification, in which—

Figure 1 represents a perspective view of my improved paper-file.

Figures 2 and 3 are detail longitudinal sections of the same.

Figure 4 is a detail perspective view of a modification of the same.

Similar letters of reference indicate corresponding parts.

This invention relates to a new paper-file, which is composed of two bars that can be tied together, so that the paper will be securely clasped between them, the strings for tying them being arranged in a peculiar manner to draw them firmly together.

The invention consists in the peculiar manner of arranging two strings on the bars, so that they can be used to firmly draw the bars together without piercing the paper.

A and B are the two bars which are used on my improved paper-file.

To one of these bars, which are both made of wood, or other suitable material, are secured pointed pins *a*, *a*, which are made to pierce the paper to be held, and which fit into holes prepared in the other bar, as indicated in fig. 2.

b and *c* are two strings, both fastened with one end to the bar A, as in fig. 1. The string *b* is secured to one end of the bar A, and is then fitted through the bar B, in the same direction in which the pins *a* are arranged, as shown in figs. 1 and 2. It is then placed on the upper edge of B, as shown. The string *c* is

fastened to the middle of the bar A, to one side of the same, and is, on the outside of the file, drawn up to the upper edge of B, through a staple, *d*, arranged thereon. It is then fitted through an eye or loop formed on the end of the string *b*, and back through the staple *d*. It is then drawn to the lower end of the file, and wound around both bars, A and B, as shown, its end being secured in a notch, *e*, which is formed in one of the bars.

Between the staple *d* and the lower end of the file, may be arranged suitable other staples, *f* *f*, to guide the lower part of the string *c*.

It will be noticed that that end to which the string *b* is secured is opposite to that at which the string *c* is fitted in the notch *e*.

The string *c*, when drawn tight, will not only stretch itself, but also the string *b*, as shown.

The strings do not pierce the paper, and can therefore be conveniently adjusted to any quantity of paper in the file.

Instead of being attached to the bar A, the string *c* may, on short files, be attached to the bar B, as shown in fig. 4, as on short files it will suffice to have the ends of the bars drawn together; while, on long files, it is desirable to also draw the bars together in the middle.

Having thus described my invention,

What I claim as new, and desire to secure by Letters Patent, is—

A paper-file, consisting of the bars A B, having the pins *a* *a*, and of the strings *b* *c*, which are interlocked, as set forth, so that they tie the bars together without piercing the paper, substantially as herein shown and described.

CHARLES W. WEST.
